[57] CLAIM

The ornamental design of a body strength and conditioning frame structure, as shown.

DESCRIPTION

FIG. 1 is a perspective view of a body strength and conditioning frame structure showing my new design; FIG. 2 is a side elevational view thereof at a reduced scale as seen from the right-hand side of FIG. 1; FIG. 3 is a side elevational view thereof opposite to the view shown in FIG. 2;

FIG. 4 is a top plan view thereof;

FIG. 5 is a front elevational view thereof; and

FIG. 6 is a rear elevational view thereof.

Fig. 4
